UNITED STATES PATENT OFFICE.

THEODORE AUGUST HARTUNG, OF AUSTIN, TEXAS.

GRAVEL DUMP.

Application filed November 8, 1923. Serial No. 673,570.

To all whom it may concern:

Be it known that I, THEODORE A. HARTUNG, a citizen of the United States, residing at Austin, in the county of Travis and State of Texas, have invented a new and useful 5 Gravel Dump, of which the following is a specification.

This invention relates to improvements in wagon construction, and more particularly 10 to the construction of the body portion thereof.

The primary object of the invention is to provide an improved wagon body of the dumping type, the floor bottom portion of 15 the body being constructed so that portions of the leg, or the entire leg may be dumped at the will of the operator.

Another important feature of the invention is to provide improvements in a device 20 of this character including means for holding the sectional bottom in its active position, novel means being provided for releasing the sections to accomplish the purpose of the invention.

With the foregoing and other objects in 25 view which will appear as the description proceeds, the invention resides in the combination and arrangement of parts and in the details of construction hereinafter described.

30 and claimed; it being understood that changes in the precise embodiment of the invention herein disclosed, may be made within the scope of what is claimed, without departing from the spirit of the invention.

35 Referring to the drawing:

Figure 1 is a plan view of a wagon bed constructed in accordance with the invention.

Figure 2 is a side elevational view there- 40 of.

Figure 3 is a sectional view taken on line 3—3 of Figure 1.

Referring to the drawing in detail, the wagon body includes side boards 5 which 45 are connected at their forward ends in any suitable and well known manner.

The side boards 5 are mounted on the channel irons 6 that are bolted or otherwise secured to the bolsters 7 on which the wagon 50 body is supported, it being understood that the channel irons 6 extend the entire length of the body.

The floor of the wagon bed or bottom in- 55 cludes a plurality of cooperating sections ar- ranged in parallel relation with each other as clearly shown by Figure 3 of the draw-

ings. Each section is formed with a hinge 8 adapted to embrace the supporting rod 9 associated therewith, whereby the sections may swing to their open or closed positions, at the will of the operator. As shown, lips 10 are formed on certain sections of the floor, which lips overlie a portion of the adjacent hinged sections to prevent material from passing between the adjacent edges of sections. The supporting rods 9 have their ends extended through the end members 11 forming a part of the wagon body.

The sections vary in length, the outer or shorter sections being designed to fall to a discharging position prior to the moving of the remaining sections so that portions of the load may be dumped independently of the remaining portion thereof. Slidably mounted at the ends of the wagon body are supporting bars 12 that have their ends disposed in slots 13 formed adjacent to the ends of the wagon body, so that the bars may slide throughout the length of the slots and allow the hinged sections forming the bottom to swing downwardly. In order that the hinged sections will closely engage the supporting bars 12, the ends of the sections extend upwardly at 14 where they overlie the supporting bars 12.

Extending through the side boards 5 at a point substantially intermediate their ends, is a rod 15, the length of the rod being greater than the width of the wagon bed to allow the ends of the rod 15 to extend beyond the side boards 5 where they support the arms 16, which arms have connection with the rods 17 and 18 respectively at points adjacent to the upper ends of the arms whereby movement of the arms 16 produces a relative movement of the rods 17 and 18.

The rod 17 has pivotal connection with the lever 19 at 20, which is manually operated to cause a movement of the rod 17 when it is desired to operate the supporting bars 12. A dog 21 is provided on the lever 19 and is designed to hold the lever in various positions of adjustment. The lower end of the lever is pivotally supported at 22 to provide for such movement of the rod, when the lever 19 is moved.

The rod 18 at the opposite side of the bed has pivotal connection with the bar 23, at 24, the lower ends of the bar being tapered and extended into an opening formed in the supporting bar 12 associated therewith,

while at the opposite side of the body portion a similar arm 25 is provided, which also has a tapered extremity fitted in an opening in the opposite end of the bar 12 associated therewith.

This arm 25 is actuated by the bar 27 that has pivotal connection with the arm 25 at 28, and has pivotal connection with the arm 16 at one side of the body at 29, whereby movement of the bar 27 is accomplished by the movement of the arms 16.

The supporting bar at the rear end of the wagon body is actuated by means of the arms 30 that are pivotally connected to the wagon body at 31 and have reduced end portions 32 extended into openings formed in the supporting bar associated therewith, the upper ends of the arms 30 having pivotal connection with the operating rods 33 that connect with the arms 16 so that movement of the bars at both ends of the wagon body will be simultaneous.

From the foregoing it will be obvious that upon movement of the bar 17 in the direction of the arrow as shown by Figure 2 of the drawing, the supporting bars at the end of the wagon body will be moved away from the ends of the sections of the bottom of the body to allow the sections to swing downwardly under the weight of the material supported thereby to discharge the load.

When it is desired to return the hinged sections of the wagon body to their normal or supporting positions, the lever 34 is operated. The lever 34 is pivotally supported at its lower end and has pivotal connection with the rod 35 that extends downwardly which in turn has pivotal connection at 36 with the supporting shaft 38 that is hollow 40 and houses the rod 15 as clearly shown by Figure 3 of the drawings.

Secured to the shaft 38 at a point adjacent to one end thereof, is a collar 39 which carries an arm 40 formed with openings to receive the lifting links 41 that have connection with sections of the bottom through the links 42 so that movement of the arm 40 will result in a relative movement of the sections associated therewith.

Collars 43 are also secured to the shaft 38 and are arranged in suitable spaced relation with each other to accommodate the members 44 that have arms 45 formed integral therewith, which arms have connection with sections of the bottom through the links 46. Shoulders 47 are formed on the collars 43 which shoulders are engaged by the laterally extending lugs 48 of the members 44 so that the bottom sections may be moved simultaneously from their open positions to their closed positions and at the same time permitting the bottom sections adjacent to one side of the wagon body may fall downwardly to discharge the contents or portion of the

load supported thereby, without effecting 65 the remaining sections of the wagon bottom, thereby permitting portions of the load to be discharged at the will of the operator.

It is therefore obvious that by operating the lever 19, to move the supporting bars 70 slightly to disengage the shorter sections of the wagon bottom, the shorter sections will be permitted to drop partially rotating the shaft 38 and moving the shoulders 47 out of engagement with the members 44, while a 75 further movement of the lever 19 will permit the adjacent sections of the bottom to swing downwardly while a still further movement of the lever 19 to move the supporting bars out of engagement with the 80 remaining bottom sections will permit the last mentioned sections to drop.

When it is desired to return the sections to their normal or supporting positions, the lever 34 is operated moving the shaft 38, 85 whereupon the shoulders 47 of the collars 43 contacting with the laterally extending lugs of the members 44 will pick up the members 44 and move them to their normal positions. When the shaft 38 is rotated by 90 a movement of the lever 34, due to the fact that members 44 have connection with the bottom sections, it is obvious that the bottom sections are moved upwardly or to their active positions. 95

It might be further stated that the movement of the rod 35 is restricted by the coiled spring 49 which has connection with the rod 35 to the link 50, the opposite end of the coiled spring being anchored at 61 to the 100 body portion.

At the ends of the body portion are eye plates 32' through which hoisting hooks may be positioned when it is desired to lift the wagon body from the running gear supporting the same. 105

I claim:

In a dumping wagon body, a sectional bottom, means for permitting the sections to be moved to their discharging positions independently of each other, a shaft extending transversely of the body, collars loosely mounted on the shaft and having shoulders, collars secured to the shaft adjacent to the first mentioned collars and having shoulders 115 adapted to cooperate with the first mentioned shoulders to move the first mentioned collars with the shaft when the shaft is rotated, and means connecting the collars to the floor sections disposed thereunder. 120

In testimony that I claim the foregoing as my own, I have hereto affixed my signature in the presence of two witnesses.

THEODORE AUGUST HARTUNG.
